UNITED STATES PATENT OFFICE.

GIBSON T. PETTICREW, OF DEER LODGE, MONTANA.

LOCK FOR FREIGHT-CAR DOORS.

1,267,900.

Specification of Letters Patent. Patented May 28, 1918.

Application filed November 5, 1917. Serial No. 200,238.

To all whom it may concern:

Be it known that I, GIBSON T. PETTICREW, a citizen of the United States, and resident of Deer Lodge, Powell county, State of Montana, have invented certain new and useful Improvements in Locks for Freight-Car Doors, of which the following is a specification.

My invention relates to locks for freight car doors, and comprises novel features of construction and combinations of parts which will be specifically defined in the claims.

The object of my invention is to provide a more efficient lock and to simplify the construction as fully as efficiency will permit. One specific object of my invention is to provide a lock which will at all times be in position for automatic engagement if the door be closed and one which has a minimum of projecting parts.

In the accompanying drawings I have shown my invention in the form which is now preferred by me.

Figure 1 shows, in perspective, adjacent parts of a door and door jamb having the lock mounted thereon.

Fig. 2 is a vertical section through the same parts on the line of the locking bolt.

Fig. 3 is a horizontal section through the parts on the line of the locking bolt.

Fig. 4 is a perspective of the locking bolt and its attached operating arms, the catch block being shown by dotted outline.

The standard type of freight car door is one in which the door is mounted to move upon guides along the outer face of the car sides. It is for this type of door that my device is intended to be applied. I have, however, not illustrated the mounting of the door as this is so well known as to make it unnecessary.

Cars having this type of doors employ a jamb 1 projecting approximately the thickness of the door, against which the face of the door abuts. Through this jamb, paralleling the side face of the car and the direction of movement of the door, is made a hole for receiving the locking bolt 2. Face plates 4 and 40 may be used to strengthen the jamb and to furnish a stronger support for the bolt.

Both ends of the bolt project beyond the jamb. That end toward the door has a transverse slot 21 and has its tip beveled or coned, as at 22. The other end has an

operating arm 5 secured thereto by which it may be turned. This arm is preferably secured so that it may itself be turned upon its axis. To this end I have shown the bolt 60 as provided with a collar 23 which has a bore 24 for the reception of a reduced end section of the arm 5, this being prevented from coming out, as by riveting over its end.

On the edge of the door 9 which contacts 65 with this jamb, is placed a casing 6, preferably made of rolled plate bent into shape. This has a tongue forming an extension of the upper end of the central section 60, which is bent inward and downward, and 70 with its tip bent forward. The part 62 forms the upper wall, part 63 the inner side wall and 64 the bottom wall of a chamber in which is a locking or catch block 7. This block is of a size to move vertically with 75 ease and enough to permit locking and unlocking.

The face 60 has a hole 61 therein, for the reception of the locking bolt 2. The body of the door is also bored, as at 90, for the 80 same purpose and the horizontal bottom end 64 of the tongue as well as the lower end of the vertical wall 63, are centrally cut away to pass the bolt end, thus forming a slot 65 in the metal.

The horizontal end section 64 of the plate is at such a level as to support the block high enough that the inclined end 22 of the bolt 2 may raise the block and permit passage of the bolt until the block drops 90 into the groove 21 of the bolt, when the door will be locked until the block is raised out of the groove.

Over the other end of the bolt is placed a casing 3, forming a chamber between it and plate 40 of depth sufficient to receive the collar 23. This is open at the front and top an amount sufficient to permit swinging the crank arms 5 between the horizontal and vertical positions. The shoulder 31 100 forms a stop for the horizontal position and 30 for the vertical position.

The horizontal position of the arm 5 corresponds with the position of the bolt in which the bottom of the groove 21 in the bolt 105 is horizontal, or that of locking engagement with the catch block 7. If the arm 5 be thrown upward, the bolt will be rocked, and the block 7 raised until the bolt is freed. The door may then be moved back.

An extension bar 52 is pivoted by pin 51, to the crank arm 5, this pivot being located

just far enough out to permit the extension arm swinging over the face of the jamb. This extension is long enough to overlap the edge of the door and its outer end is provided with means adapted to engage a member carried by the face of the door, so that a seal of any approved type may be used to seal the two together.

The construction preferred is to have a tongue 55 projecting from the side of the casing 6 and provide the end of the arm 52 with a slot 53 to fit over the tongue 55, and provide each of these parts with registerable holes 54 and 57, through which a standard sealing strip may be passed. I may also, if desired, provide the tongue 55 with a hole 56, which would come outside the lever or arm 52, through which may be placed a securing pin, or the hasp of a padlock.

20 When the door is opened, the extension bar 52 will drop into vertical position, because the connection of the crank arm 5 with the bolt is a rotative one. In this position it is out of the way and not likely to be damaged.

25 What I claim as my invention is:

1. A car door lock comprising a rotatively mounted bolt placed with its axis in line with the direction of movement of the door at closing and with an end projecting, said projecting end having a transverse groove, a socket piece placed to receive said projecting end when the door is closed, a block movably mounted in said socket piece and adapted to be entered in the transverse groove of the bolt, and means for turning the bolt on its axis to displace said block.

2. A car door lock comprising a rotatively mounted bolt having a transverse groove near one end and held against end-wise reciprocation, with the grooved end projecting, a socket member placed to receive the projecting grooved end of the bolt, a movable catch associated with the socket member and adapted to enter the transverse groove of the bolt when the bolt is inserted within the socket, the bolt with its associated parts and the socket member with its associated parts being mounted, one on the door and the other on the door jamb, and an arm secured to the bolt and projecting laterally therefrom, by which the bolt may be turned.

3. A car door lock comprising a bolt rotatively mounted in the door jamb with its axis parallel the line of movement of the door in closing, one end of said bolt projecting beyond the face of the jamb and having a transverse groove on its upper side, a socket member mounted on the door to receive the end of the bolt, said socket member containing a chamber extending upwardly from the bolt-receiving socket, a vertically movable catch block fitting loosely in said chamber and adapted to enter

the transverse groove in the bolt, and means for turning the bolt to release it.

4. A car door lock comprising a bolt rotatively mounted in the door jamb with its axis parallel the line of movement of the door in closing, one end of said bolt projecting beyond the face of the jamb and having a transverse groove on its upper side, a socket member mounted on the door to receive the projecting end of the bolt, said socket member containing a chamber extending upwardly from the bolt-receiving socket, a catch block vertically movable in said chamber and adapted to enter the transverse groove in the bolt, a crank arm secured to the bolt and accessible for manual engagement, and means for normally holding the bolt with its transverse groove up.

5. A car door lock comprising a bolt rotatively mounted in the door jamb with its axis parallel the line of movement of the door in closing, one end of said bolt projecting beyond the face of the jamb and having a transverse groove on its upper side, a socket member mounted on the door to receive the end of the bolt, said socket member containing a chamber extending upwardly from the bolt-receiving socket, a catch block vertically movable in said chamber and adapted to enter the transverse groove in the bolt, a crank arm secured to the bolt to turn it and seal-locking mechanism for holding the bolt in locking position.

6. A car door lock comprising a bolt rotatively mounted in the door jamb with its axis parallel the line of movement of the door in closing, one end of said bolt projecting beyond the face of the jamb and having a transverse groove on its upper side, a socket member mounted on the door to receive the end of the bolt, said socket member containing a chamber extending upwardly from the bolt-receiving socket, a catch block vertically movable in said chamber and adapted to enter the transverse groove in the bolt, an arm secured to the bolt for turning it and projecting just beyond the face of the jamb, and an extension lever pivoted to the end of this arm and adapted to swing over the jamb and overlap the door, and means for sealing this extension lever to the door.

7. A car door lock comprising a bolt rotatively mounted in the door jamb with its axis parallel the line of movement of the door in closing, one end of said bolt projecting beyond the face of the jamb and having a transverse groove on its upper side, a socket member mounted on the door to receive the end of the bolt, said socket member containing a chamber extending upwardly from the bolt-receiving socket, a catch block vertically movable in said chamber and adapted to enter the transverse

groove in the bolt, an arm axially pivoted upon the bolt and projecting just beyond the face of the jamb, an extension lever connected by the outer end of said arm by a transverse pivot and adapted to overlap its end on the door, a member carried by the door in position to engage the end of said extension lever, said member and the end of the extension lever being provided with registrable seal-receiving openings.

8. A car door lock comprising a rotative bolt extending with its axis paralleling the direction of movement of the door in closing and with an end projecting and provided with a transverse groove, a laterally projecting operating handle secured to the other end of said bolt, a bolt casing having two separated walls lying one at each side said handle, the chamber formed by said walls being open to permit the projection and swinging of said arm between the positions corresponding with the locked and unlocked positions of the bolt, and a socket member for receiving the projecting end of the bolt and having a vertically movable locking block adapted to enter the transverse slot in the bolt.

9. A lock for sliding doors comprising a bolt mounted to turn and with its axis extending in the direction of the movement of the door, the end of this bolt projecting and having a transverse notch, an arm projecting laterally from the bolt, a casing inclosing said arm and having an opening permitting the swinging movement of the arm needed to unlock the bolt, a co-operative member secured to the other part of the door construction and having an opening for the reception of the projecting end of the bolt, said member having a partition wall inward from its outer face forming a chamber into which the lower end of the bolt enters, and a locking block freely slideable vertically in said chamber and adapted to enter the transverse notch in the bolt.

10. A lock for sliding doors comprising a bolt mounted to turn and with its axis ex-

tending in the direction of the movement of the door, the end of this bolt projecting and having a transverse notch, an arm projecting laterally from the bolt, a casing inclosing said arm and having an opening permitting the swinging movement of the arm needed to unlock the bolt, a co-operative member secured to the other part of the door construction and having an opening for the reception of the projecting end of the bolt, said member having a partition wall inward from its outer face forming a chamber, the lower end of said partition extending outward toward the outer face of the member to form a support for the locking block and having a central slot for the reception of the end of the block, and a locking block freely slideable vertically in said chamber and adapted to be raised by the end of the bolt and to then enter the transverse slot in the bolt.

11. A lock for sliding doors comprising two members mounted respectively upon the door and the door jamb, one of said members having a bolt mounted to turn upon its axis and extending in the direction of the movement of the door, the end of said bolt projecting and having a transverse slot and having an upper beveled surface between said slot and its outer end, an arm secured to and extending transversely from the opposite end of the bolt, a casing plate outwardly of said arm and in which the bolt is journaled, said plate having stop surfaces limiting the swing of the arm between locked and unlocked positions of the bolt, the other member of the lock having a chamber into which the projecting end of the bolt enters, a locking member vertically movable in said chamber and adapted to enter the transverse slot in the bolt and a support for said locking member holding it in position for engagement by the beveled end of the bolt to be lifted thereby.

Signed at Deer Lodge, Montana, this 25th day of October, 1917.
